UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF CRACKING OIL

Application filed June 26, 1926. Serial No. 118,828.

This invention relates to improvements in a process of cracking oil, and refers more particularly to the treatment of pressure distillate as part of a continuous cracking process.

The object of the invention is to treat the pressure distillate as it comes from the top of the dephlegmator so as to decolorize and deodorize the pressure distillate, and make a finished motor fuel, as for example, having an end point corresponding to gasoline.

The invention will be understood from the following description, reference being had to the accompanying drawing in which the single figure is a side elevational view illustrating the apparatus.

Referring to the drawing, 1 designates a furnace in which is mounted the heating coil 2. The transfer line 3 having valve 4, leads to one end of the expansion chamber 5. This expansion chamber 5, which is preferably located outside of the fire zone, has residue drawoff 6 controlled by the valve 7 and vapor outlet pipe 8 extending into the lower end of the dephlegmator 9 as shown. This dephlegmator 9 has the reflux condensate drawoff pipe 10 having valve 11, and may be provided with hot oil pump 12 leading to the main feed line 13. The feed line 13 may be supplied with raw oil through the pump 14 leading to any suitable source of supply. The vapors pass out of the top of the dephlegmator through the pipe 15 controlled by the valve 16. Instead however, of passing directly to

the water condenser, or to another fractionating tower as is the case in the cracking processes now in use, I pass the hot vapors from the top of the dephlegmator through a filter press 17, which filter press may be of the conventional type, using layers of filtering material such as fuller's earth, diatomaceous earth or the like. If desired, a hot vapor pump 18 may be interposed in the line 15 so as to put the filter press under a higher pressure than the balance of the system. However, the pump may be by-passed in an obvious manner, if desired. As the vapors pass through the filter press, they are decolorized and deodorized.

They then pass either directly to the water

condenser and receiver, or if desired, may pass through the line 19 having the valve 20, to a still 21, which still 21 is equipped with a fractionating tower 22 having liquid drawoff 23 controlled by the valve 24 and vapor outlet pipe 25 controlled by the valve 26 leading to the water condenser 27 and thence to the receiver 28. This receiver 28 may be equipped with gas outlet pipe 29 controlled by the valve 30, liquid drawoff pipe 31 controlled by the valve 32. The still may have residue drawoff 33 controlled by the valve 34.

By suitably regulating the valve 20, the pressure on the vapors or oil as they enter the still may be substantially reduced, thus causing the oil to flash, and the lightest or having an end point corresponding to gasoline portions thereof pass through the tower into the receiver. If desired, the still 21 may be externally heated as the filter press might in some cases be cooled, and the oil comes from the filter press in more or less liquid condition. If desired, the vapors from the dephlegmator may be cooled to liquid form before they enter the filter press.

The arrangement is such that the entire system may be maintained under uniform pressure of say 200 pounds, or the filter press may be maintained under higher pressure than the preceding part of the apparatus, as for example, 300 pounds, and the gasoline still may be maintained under a pressure of 50 pounds or atmospheric.

I claim as my invention:

1. A method for refining the vaporous hydrocarbon mixture issuing from an oil cracking process which comprises dephlegmating said mixture and condensing therefrom fractions heavier than gasoline while retaining the gasoline hydrocarbons in vapor form, increasing the pressure on said gasoline hydrocarbons and passing the same under the increased pressure through a decolorizing and deodorizing filtering agent.

2. A method for refining the vaporous hydrocarbon mixture issuing from an oil cracking process which comprises dephlegmating said mixture and condensing therefrom fractions heavier than gasoline while retaining the gasoline hydrocarbons in vapor form,

passing the gasoline vapors under pressure through a decolorizing and deodorizing filtering agent, cooling the vapors during their passage through said agent thereby rendering the same more or less liquid, passing the liquid to a distillation zone maintained under lower pressure than the filtering stage whereby distillation therein is facilitated by the pressure reduction, and condensing the vapors evolved in said distillation zone.

GUSTAV EGLOFF.
